United States Patent Office

Des. 177,314
Patented Apr. 3, 1956

177,314

CASING FOR A THERMOSTAT OR THE LIKE

Rooney W. Davis, Webster Groves, Mo., assignor to
Missouri Automatic Control Corporation, St. Louis,
Mo., a corporation of Missouri

Application November 15, 1954, Serial No. 33,087

Term of patent 14 years

(Cl. D52—7)

FIG. 1

FIG. 2

FIG. 4

FIG. 3

Fig. 1 is a plan view of a casing for a thermostat showing my new design;

Fig. 2 is a front elevation thereof;

Fig. 3 is a bottom view thereof; and

Fig. 4 is a side elevation thereof.

I claim:

The ornamental design for a casing for a thermostat, or the like, substantially as shown.
